(57) **CLAIM**

The ornamental design for a light kit, as shown and described.

DESCRIPTION

FIG. 1 is a perspective view of a light kit showing my new design.

FIG. 2 is a front elevation view of the light kit of FIG. 1.

FIG. 3 is a rear elevation view of the light kit of FIG. 1.

FIG. 4 is an enlarged first end elevation view of the light kit of FIG. 1.

FIG. 5 is an enlarged second end elevation view of the light kit of FIG. 1.

FIG. 6 is a top plan view of the light kit of FIG. 1; and, FIG. 7 is a bottom plan view of the light kit of FIG. 1. The aspects shown in broken lines are not considered a portion of the claimed ornamental design. The break lines in some of the figures are a symbolic break and indicate that any portion of the light kit between the break lines forms no part of the claimed design.
